UNITED STATES PATENT OFFICE.

JOHN FEULNER, OF MIDDLETOWN, CONNECTICUT.

NECKBAND.

Application filed June 28, 1921. Serial No. 430,999.

To all whom it may concern:

Be it known that I, JOHN FEULNER, a citizen of the United States, and a resident of Middletown, in the county of Middlesex and 5 State of Connecticut, have invented a new and Improved Neckband, of which the following is a full, clear, and exact description.

The present invention relates to new and useful improvements in wearing apparel and 10 it pertains more particularly to a neckband for shirts.

It is one of the objects of the present invention to so construct a neckband that the shape of the same is formed during the process of weaving of the fabric from which the 15 neckband is made.

It is a further object of the invention to provide a neckband in which the edge presented will be round and soft, thus eliminating 20 the possibility of fraying of the edge with the consequent discomforts thereof to the wearer.

It is a further object of the invention to construct a neckband in such a manner that 25 the inner face thereof will be soft and comfortable to the neck of the wearer.

It is a further object of the invention to so construct a neckband that stitching or 30 sewing in the manufacture of the band is greatly reduced.

It is a further object of the invention to weave the neckband in such a manner that the use of folding machines to cause the 35 band to properly position, is eliminated.

With the above and other objects in view, reference is had to the accompanying drawings, in which—

Figure 1 is a perspective view of a completed neckband constructed in accordance 40 with the present invention;

Fig. 2 is a detail perspective view of a portion of an uncompleted neckband;

Fig. 3 is an enlarged cross sectional view taken on the line 3—3 of Fig. 2, showing 45 the weave of the neckband;

Fig. 4 is an enlarged sectional view taken at right angles to Fig. 3 on the line 4—4 of Fig. 2.

Referring more particularly to the drawings, the neckband comprises an outer section 5 of a two-ply plain weave of any suitable material, such, for example, as silk, twill, or the like. The two plies of this outer section 5 are woven in a manner clearly 55 shown in Figs. 3 and 4, and the section 5 consists in addition to the warp and weft

threads 6 and 7, of a binder 8 and a filler 9. By this construction it is apparent that the outer section 5 of the neckband is of tough heavy material well adapted to withstand the wear and abuse to which articles of this nature are subjected in use. At substantially half-way between the side edges of the completed neckband the two plies are separated to form spaced wings 10 and 11. 60 The reference character 11 designates the inner wing and in weaving the neckband the warp threads are crowded by means of a suitable constructed reed to provide a relatively thin portion 12. This relatively thin 65 portion 12 extends throughout the length of the neckband and tends to permit of a more ready folding of the neckband without bulk at the point of fold.

After the neckband has been so formed, 75 it is provided at the proper points with buttonholes or the like 15, and after the neckband has been folded, it is stitched at the ends 16, which is the only stitching done in order to form a completed article. 80

In attaching the neckband to a shirt or similar garment, the two wings 10 and 11 are spread and the defining edge of the neck opening of the garment is placed therebetween, after which the two wings 10 and 11 85 are stitched together through the defining edge of the neck opening and the neckband is stitched to place.

In some instances it may be desired to stitch the reinforced or outer section 5 to 90 the shirt with the neckband, or, if desired, this portion may be left detached.

While in the present instance a single neckband has been described, it is obvious that the neckband may be woven in lengths 95 of such dimension that several neckbands may be included, and that the same may be cut and used as desired. It is also obvious that buttonholes may be woven into the neckband during the process of manufacture or 100 may be separately worked, neither of which constructions, however, forms a particular part of the present invention.

From the foregoing it is apparent that the present invention provides a neckband 105 for shirts, which is capable of great wear-resisting qualities, and, at the same time, provides means by which the attachment of the neckband to a shirt is greatly facilitated. Furthermore, a neckband constructed in accordance with the present invention presents 110 an outer fabric adapted to receive the wear

of stiff collars and the like, which neckband is capable of resisting said wear, and, at the same time, presents an inner face which is soft and pliable and not unduly uncomfortable to the wearer thereof.

5 I claim—

1. As an article of manufacture, a neckband for garments, said neckband comprising an integral woven fabric body adapted to be folded longitudinally, said integral fabric body consisting of a single element of double ply on one side of the line of fold and a plurality of elements of single ply upon the other side of the line of fold, and a weakened portion extending throughout one of the elements of single ply and arranged therein adjacent its point of connection with the element of double ply.
- 10 2. As an article of manufacture, a neckband for garments comprising a single piece of material woven to provide a single outer

section of double ply and a double inner section, each of the elements of said double inner section being single ply and formed integral with each other and integral with the outer section.

- 15 3. As an article of manufacture, a neckband for shirts comprising a single piece of material constructed in its weaving in such a manner as to provide an outer section consisting of a single member of multiple ply and an inner section consisting of a plurality of members of single ply, one of the members of the inner section being formed with a weakened portion extended throughout its length adjacent its point of juncture with the outer section and the other member, said neckband adapted to be folded longitudinally adjacent the point of juncture of the inner and outer sections.

JOHN FEULNER.
